UNITED STATES PATENT OFFICE.

PERCY H. THOMAS, OF UPPER MONTCLAIR, NEW JERSEY.

ELECTRIC INSULATOR.

1,273,015.

Specification of Letters Patent. Patented July 16, 1918.

Application filed August 29, 1918. Serial No. 737,243.

To all whom it may concern:

Be it known that I, PERCY H. THOMAS, a citizen of the United States of America, and a resident of Upper Montclair, county of 5 Essex, State of New Jersey, have invented certain new and useful Improvements in Electric Insulators, of which the following is a specification.

My invention relates to electric insulators 10 of the class particularly adapted for high tension electric lines although it may as well be used in connection with other electrical uses than with high tension. It is desired, among other objects, to provide an insulator 15 of the suspension type which is adapted for extra-high tension service. Other objects, advantages and purposes of this type of insulator are set forth at greater length in the specification of my application for patent, 20 Serial No. 767,995, filed May 16, 1918, to which reference is hereby expressly made.

In the following I have described, in connection with the accompanying drawings, a 25 number of different forms of devices illustrating the application of the principles of my invention.

In the drawings Figure 1 is a vertical sectional view of an insulator showing one 30 way of practising my invention; Fig. 2 is a top plan view, partly broken away, of the insulator shown in Fig. 1; Fig. 3 is a view similar to Fig. 1 showing a modification; Fig. 4 is a cross sectional view of a device similar to that shown in Fig. 3 along the 35 line A—B; Figs. 5 and 6 are vertical sectional views respectively illustrating two other modifications of design; Fig. 7 is a plan view showing a detail of one of the parts of Fig. 6; Fig. 8 is a vertical sectional 40 view of another form of insulator showing still another way of carrying out the principles of my invention; Fig. 9 is a vertical sectional view showing another form of insulator embodying the principles of my invention; Fig. 10 is a top plan view of the 45 device shown in Fig. 9 with the rain guard removed; Fig. 11 is a sectional view, partly broken away, of the parts shown in Fig. 10 along the line G—H; and Fig. 12 is a vertical 50 sectional view of a modification of the type of insulator shown in Fig. 9.

Similar numerals of reference indicate similar parts throughout the several views.

In constructing the main body of my 55 insulator I prefer to use a material having a high dielectric quality and one capable of

being obtained of high quality and of great uniformity. Porcelain or glass are suitable materials for the purpose. In cementing certain of the parts together any suitable 60 cement may be used and either Portland cement or cement made of litharge and glycerin will give good satisfaction. The metal parts of the insulator may be of any suitable metal giving the desired mechanical 65 strength and malleable cast iron or steel forgings are suitable for the purpose. The rain guards which are adapted to improve the electrical efficiency of the insulator and to control the distribution of the electrical 70 field may be of any suitable material such as galvanized iron.

The insulator shown in Figs. 1 and 2 comprises a cylindrical piece of dielectric material 26, having circular grooves 27—27 at 75 each end thereof, midway between the inner and outer walls of the cylinder. The short length of pipe 28—28 is adapted to fit into the circular grooves 27 and to be cemented therein. Pipes 28 are internally 80 screw threaded at their outer ends to receive a screw threaded metal block 29 carrying an eye or socket 30. 31 is a circular or disklike rain guard, screwed, bolted, or otherwise fastened to pipe 28 adjacent to 85 the ends of the cylinder 26. The outer periphery of the rain guard 31 is curled or turned downwardly in the form of a bead 32. This may be conveniently done by turning the edge of the rain guard over a wire. 90 The rain guard extends diametrically from the cylinder 26 a sufficient distance to prevent the rain from dripping down the cylinder while at the same time the rain guard acts as a distributor of the electric field in 95 order to improve the electrical efficiency of the device. The purpose of the bead is to avoid a sharp edge on the rain guard and it is turned down to permit the rain to fall off gradually as it comes rather than retaining 100 the same so that it will fall off intermittently in larger quantities. 33—33 are air spaces between the blocks 29 and the ends of cylinder 26.

In Fig. 3 the cylinder 26 is shown without 105 the circular recesses at the ends. In this figure the blocks 29 are provided with recesses 34 to receive the ends of cylinder 26, the blocks entering a short distance into the space within the cylinder as shown. Rain 110 guards 31 are shown as fastened to the blocks 29 and instead of extending at right

angles to the cylinder 26 they are bent downward from the plane shown in Fig. 1.

Fig. 4 shows an insulator, similar to that of Fig. 3, in which the tube or block 26 is made in three segments to accommodate the expansion and contraction of the blocks 29.

In Fig. 5 the cylinder is shown in the form of a double U-shaped piece in cross section, joined together at the top by a bridge 35, thus having air spaces 36 and 37 within the same. The blocks 29 are provided with suitable recesses to receive the respective ends of the cylinders which are cemented in said blocks. The rain guards 31 are fastened to the blocks 29. This form provides two cylinders of insulating material, thus giving greater strength while preventing a direct discharge through air between blocks 29 inside the insulator.

20 In Fig. 6 the insulator is shown as comprising the cylinder 26 of dielectric material having shoulders or recesses 38—38 near each end thereof on the inside. A spring clamp 39 carrying a ring 30 is adapted to be sprung into the recesses 38. In this form the rain guard is not shown but may be added in the manner shown in connection with the other forms described.

Fig. 8 shows an insulator comprising 30 cylinders 40 and 41 of dielectric material, cylinder 40 being flared out at the bottom and recessed at the inner end to receive the upper end of cylinder 41. The top of cylinder 40 and the bottom of cylinder 41 are each provided with shoulders 42 to which are cemented metallic clamps 43 carrying rings 30. The rain guards 31 are shown as fastened to the clamps 43. 44—44 are metallic cores cemented to the ends of cylinders 40 and 41 respectively and joined together by a coupling 45 screw threaded to the inner ends of cores 44—44 respectively so that the two parts of the insulator may be closely drawn together by rotating one with reference to the other. The ends of cylinders 40 and 41 are closed by bridges 46 of dielectric material and provided with shoulders 47 arranged at right angles to the line of strain caused by the pull of the cores 50 44—44 of said cylinders. The ends of the cores 44—44 are also provided with shoulders 48 at right angles to the line of strain above described and parallel to the shoulders at the ends of cylinders 40—41. The purpose of the shoulders 47—48 is that when the parts are cemented together the line of strain will be such as to be perpendicular to the cement surfaces. 49 is an air space within cylinders 40 and 41 surrounding cores 60 44—44.

Figs. 9, 10 and 11 show an insulator comprising a cylinder 83 of dielectric material provided with circular flanges 84—84 and a bridge 85 separating the two ends of the cylinder from each other. Each end of the

cylinder is provided with recesses 86 arranged circumferentially (Fig. 10) of the respective ends of the cylinder. The cylinder at each side of recesses 86 is flared inwardly and outwardly to form a strengthened wall for the recesses 86. 87 is a metal cap piece carrying pins 88 adapted to be cemented in recesses 86. Rain guard 89 is preferably integral with cap 87. The periphery of the rain guard 89 is provided with a rounded edge as shown. Rings 90 are carried by the cap pieces 87. This form provides a large number of small points of application of strain to the insulating material, which relieves the latter mechanically and at the same time is simple and economical to construct.

Fig. 12 shows an insulator comprising a plurality of cylinders of dielectric material, cylinders 91—91 being similar to each other and each closed at one end by a bridge 92 of dielectric material. The connection between the cap piece 87 and the cylinder 91 is somewhat similar to that described in connection with the insulator shown in Fig. 9. 90 Cylinders 91 and 93 are joined together by pins cemented in recesses at the adjacent ends of said cylinders. Opposite the recesses formed to receive the connecting pins the respective cylinders are flared outwardly as shown at 94 and also provided with ribs 95. The purpose of the flared out portion and of the ribs 95 is to strengthen the dielectric material opposite said recesses. The caps 87 are connected to the respective ends 100 of the cylinders 91 by means of pins 96 the lower ends of which are cemented in the recesses 86 in the ends of the cylinders while the upper ends are provided with heads 97 resting on washers 98 of any suitable material such as asbestos, leather, lead, etc. the shank of the pin having a slight play in perforations 99 through the cap piece 87, the cap piece being provided with suitable recesses or shoulders 100 to receive the heads 110 97 of pins 96. This construction is especially effective in relieving the insulating material from all stresses due to the expansion, contraction or deformation of the cap pieces 87. Ribs 101 are also shown as being 115 disposed adjacent the flared outside portions of cylinders 91 opposite the recesses to provide additional strengthening means for the dielectric material.

It is obvious that I do not restrict myself to any particular type of construction, the forms shown being simply illustrative of various ways of carrying out the principles of my broad idea.

What I claim and desire to secure by Letters Patent is:

1. A line insulator comprising a tube of vitreous material having straight sides, metal hanger pieces fitted to each end and means for transmitting the entire load to be 130

carried by the insulator directly from the hanger pieces to the walls of the tube.

2. A line insulator comprising a tube of vitreous material and means for transmitting the entire load to be carried by the insulator directly to the walls of the tube comprising metal hanger pieces taking directly into the tube at each end thereof.

3. A line insulator comprising a tube of vitreous material and means for transmitting the entire load to be carried by the insulator directly to the walls of the tube comprising metal end caps provided with flanges adapted to engage both the inner and the outer surfaces of the ends of the tube.

4. An insulating support comprising a metal hanger attached to the support, a second metal hanger attached to the object to be supported and means for insulating said hangers from each other and for carrying the entire load to be supported, said means consisting of a tube of vitreous material having its ends fitted to and secured in said metal hangers.

5. An insulating support comprising a supporting and insulating member of vitreous material in the form of a hollow cylinder, end caps fitted to and inclosing the ends of the cylinder and means for securing the end caps to the walls of the cylinder whereby the entire load is carried by said cylinder.

6. In an electric insulator, an insulating, load-carrying member, comprising a tube of vitreous material, and metal end caps fitted and secured to the ends of said tube, said tube being the only mechanical connection between said end caps.

7. A strain supporting line insulator, comprising metallic end pieces attached respectively to the line conductor and the supporting structure, and an elongated insulating tension member for connecting said end pieces, said insulating member being of vitreous material, hollow, and having a thin wall of uniform thickness and stress resisting means for securing said end pieces to the surface of the wall of said insulating member.

8. A line insulator comprising a single, hollow, tubular member of vitreous material, metal caps at each end thereof, means for distributing the stress from the caps to the tubular member and through both the inner and outer surfaces of the ends thereof, and pivotal suspension means for said tubular member.

9. A terminal cap for a swinging line insulator comprising a metallic cone-shaped piece having pivotal suspension means at the apex, and an encircling flange at its base for gripping the tension member on both the inner and outer surfaces of the ends thereof.

10. A line insulator comprising a hollow insulating member, metallic end caps therefor closing said hollow member and having projecting portions adapted to engage both inside and outside the wall of said insulating member at the ends thereof.

11. A line insulator comprising a tube of vitreous material and metallic end caps therefor closing the ends of said tube and extending beyond the side walls of the tube to form a rain guard, said caps being provided with flanges adapted to engage both the inner and outer surfaces of the ends of the tube.

12. A line insulator comprising a tubular tension member of vitreous material having an open end and open interiorly continuously from end to end, means for transmitting the entire mechanical load to be carried by the insulator directly to the walls of said tubular member, said means comprising caps of electrically conductive material respectively carried directly by the walls of said tubular member at the ends thereof, and means for preventing an electrical discharge through the interior of said tubular member.

In testimony whereof I have signed this specification in the presence of two subscribing witnesses.
